UNITED STATES PATENT OFFICE.

FRANCIS EVERARD LAMPLOUGH AND HENRY JOHN SCOTT STOBART, OF SMETHWICK,
ENGLAND.

VALVE-OPERATING MECHANISM.

1,369,677.

Specification of Letters Patent. Patented Feb. 22, 1921.

Application filed September 8, 1919. Serial No. 322,597.

To all whom it may concern:

Be it known that we, FRANCIS EVERARD LAMPLOUGH, M. A., and HENRY JOHN SCOTT STOBART, residing at Lighthouse Works, 5 Smethwick, in the county of Stafford, England, subjects of the King of Great Britain and Ireland, have invented certain new and useful Improvements Relating to Valve-Operating Mechanism, of which the following

10 is a specification.

In connection with lighthouses, light-buoys and the like, gas valves under the control of solar radiations are sometimes used. The object of the present invention is to 15 construct an improved valve of this kind.

According to the present invention we employ a pair of chambers containing saturated vapor in contact with its liquid, and utilize for producing the desired movements 20 the difference of pressure which arises when as a result of a temperature difference the mass of saturated vapor is increased in one chamber and diminished in the other.

The accompanying drawings at Figures 25 1 and 2 illustrate diagrammatically two means for carrying the invention into effect.

Fig. 3 illustrates an arrangement of check valve.

Referring to Figs. 1 and 2, a pair of 30 closed glass chambers α , α' connected by a tube b are carried on a cradle c pivoted at e . One of the chambers, $e. g.$, α' , is plain or silvered or protected from radiation by a shield, and the other, α , blackened externally, 35 so that when exposed to solar radiations an increase of temperature is produced in the blackened chamber. The tube and lower portion of each chamber is filled with mercury, and a quantity of volatile liquid (such as 40 ether) is placed on the mercury in each chamber. The region in each chamber above the surface of the liquid is occupied by the vapor of the liquid, the air originally present having been evacuated as completely as the 45 working conditions of the apparatus may require. Normally in darkness the two liquid surfaces are at the same level. When a temperature difference due to solar radiations is set up between the chambers the 50 quantity of vapor increases by evaporation in one chamber and decreases by condensation in the other until the excess of vapor pressure corresponding to the excess of temperature is balanced by the head of the

extra amount of mercury which has been 55 forced from one chamber into the other. The equilibrium of the system is therefore altered with the result that the cradle c tilts. This movement is caused to close the gas valve d . Equalization of the temperature 60 causes the original equal condition of vapor pressure to be restored, and the return of the cradle c opens the valve d .

In the arrangement shown the cradle c transmits motion through a strut f to a 65 lever g . In Fig. 1 this lever actuates the valve d through a rod f' , and in Fig. 2 the lever is attached directly to the valve. Two different forms of valves are shown as examples. The lever g is supported on a 70 knife edge bearing h , and at the end opposite the valve is acted on by an adjustable spring i . The valve is contained in a chamber j which is closed on one side by a flexible diaphragm k . Gas enters the chamber 75 through an open pipe l and passes out through a pipe m whose upper end is controlled by the valve. The spring i serves to assist in the restoring of the lever system to its original position when a condition of 80 equal temperature is attained in the bulbs. When the lever system is tilted by the operation above described this spring is compressed sufficiently to produce the required 85 restoring force.

Preferably, the upper parts of the bulbs are extended by short stems n n' (Fig. 2) terminating in small spherical bulbs o o' , the bulb o and its stem if necessary being silvered or left transparent while the other 90 o' is blackened. When a considerable temperature difference exists between the two bulbs, the fluid would tend to be forced up into the silvered or transparent bulb a' so as completely to fill it. The blackened upper 95 portion consisting of the stem and terminal bulb, however, maintains within it a temperature comparable with that of the blackened bulb a . Consequently if the fluid in a' is pressed up into the terminal stem and bulb 100 its vapor pressure increases and balances that in the other bulb. The vapor phase in the less heated bulb a' therefore never completely disappears. But for this precaution the fluid might completely fill the bulb a' 105 and the reluctance to the reformation of the vapor phase would interfere with the restoration of the original conditions with equal-

ization of temperature. Alternatively to prevent automatically excessive displacement of fluid from the chamber a to the chamber a' the former may be fitted with a 5 check valve q (Fig. 3) in the form of a float. When the fluid level in a descends sufficiently the valve rests on the outlet from the chamber and closes it.

Owing to the fact that the relative increase 10 of vapor pressure is much greater the higher the temperature, it may be desirable to have a compensating device which, while allowing the apparatus to be designed so that it is sufficiently sensitive at low temperatures, 15 will prevent its being too sensitive at higher temperatures. Such a device may take the form of a bent compound sheet of metal ν as shown in Fig. 2. This exerts no effect on the cradle c at the low temperatures existing 20 during the winter months, but expands when the temperature rises and exerts a force tending to check the turning of cradle on its pivot, thus diminishing the sensitiveness during the hotter summer months.

25 Instead of a saturated vapor in contact with its liquid we may use the equivalent combination of a gas in contact with its saturated solution. For instance, the apparatus may be partly filled with a saturated 30 solution of ammonia with ammonia gas above the liquid.

The valve is applicable to a variety of uses other than those mentioned. For example it may be applied to factory, station 35 and street lighting systems.

Having thus described our invention what

we claim as new and desire to secure by Letters Patent is:—

1. In valve operating mechanisms controlled by solar radiations, the combination 40 comprising a pair of chambers adapted to be unequally heated by solar radiations, a passage connecting the lower ends of said chambers, mercury contained in said passage and the lower parts of the chambers, each 45 chamber containing saturated vapor in contact with its liquid which is supported on the surface of the mercury, a pivoted support for the chambers, a gas controlling valve, and means for imparting movement to the 50 valve with the movement of the chambers and their support, substantially as described.

2. In valve operating mechanisms controlled by solar radiations, the combination comprising a pair of inter-communicating 55 chambers adapted to be unequally heated by solar radiations and each containing saturated vapor in contact with its liquid, an extension at the upper end of each chamber, the said extension being adapted to be affected by solar radiations differently from the main portion of the chamber, a pivoted support for the chambers, a gas controlling valve, and means for imparting movement to the valve with the movement of the chambers 60 and their support, substantially as described.

In testimony whereof we have signed our names to this specification.

FRANCIS EVERARD LAMPLOUGH.
HENRY JOHN SCOTT STOBART.
